UNITED STATES PATENT OFFICE.

SAMUEL E. BURKETT, OF PITCAIRN, PENNSYLVANIA.

PUMP.

Application filed January 12, 1921. Serial No. 436,714.

To all whom it may concern:

Be it known that I, SAMUEL E. BURKETT, a citizen of the United States, residing at Pitcairn, in the county of Allegheny and 5 State of Pennsylvania, have invented certain new and useful Improvements in Pumps, of which the following is a specification.

This invention relates to pumps particularly adaptable for use as an accessory for motor vehicles, and the primary object of the invention is to provide an improved pump constructed so that its base can be readily removed, thereby permitting different types of bases to be associated therewith, so that the pump can be used either for pumping air or for pumping water.

A further object of the invention is to provide a novel type of pump for facilitating 20 the filling of vehicle radiators from streams and the like, when the vehicle is on the road, which embodies a novel valve structure for controlling the flow of water into and from the pump base, the pump having a novel 25 type of nozzle for engaging the radiator filling tube.

A still further object of the invention is to provide an improved combination pump for motor vehicles of the above character, 30 which is durable and efficient in use, one that is simple and easy to manufacture, and one which can be placed upon the market at a reasonable cost.

With these and other objects in view, the 35 invention consists in the novel construction, arrangement and formation of parts, as will be hereinafter more specifically described, claimed and illustrated in the accompanying drawings, forming a part of this specification, in which drawings:

Figure 1 is a side elevation of the improved pump, the barrel thereof being shown in section.

Figure 2 is an enlarged fragmentary longitudinal section through the lower end of 45 the pump, illustrating the pump barrel connected with the novel pump base which is utilized when the pump is to be used for elevating water.

Figure 3 is a top plan view of the improved base which is adapted to be connected with the pump barrel, when the pump is to be utilized for elevating water.

Referring to the drawings in detail, where- 55 in similar reference characters designate corresponding parts throughout the several

views, the letter A indicates the pump barrel or cylinder; B, the piston and its component parts; and C, the detachable base used when the pump is to be utilized for 60 pumping water.

The pump barrel A includes a hollow cylindrical body 10 having its opposite ends open and externally threaded as at 11 and 12. The upper end of the cylindrical body 10 has arranged thereon a disc washer or plate 12 and this plate is held in position by means of a cap 13, which is provided with a stuffing box 14, through which extends the piston rod 20 of the piston B and its component parts. The upper surface of the stuffing box 14 is concaved, as at 15 for the reception of the packing 16 and the stuffing box cap 17 forces the stuffing or gasket into engagement with the piston rod 20.

The piston B is of the usual cup form and includes the upper and lower plates 18 and 19, between which is adapted to be positioned the flexible disc 21, the outer edge of which is extended beyond the plates 18 and 19 and downturned, as clearly shown in the drawings. The plates 18 and 19 and the intermediate gasket 21 are mounted upon the reduced end 22 of the piston rod 20 and this reduced end is provided with threads for 85 the reception of the retaining nut 23, which holds the piston in place on the piston rod. The upper end of the piston rod 20 has a suitable handle 25 mounted thereon, and upper and lower wear plates 26 and 27 are pro- 90 vided for engaging the upper and lower surfaces of the handle, and the handle is held in position by means of a retaining nut 28 which is threaded on the upper end of the piston rod 20. It can be seen that by raising 95 and lowering the handle 25 that the piston B will be actuated. In order to effectively cool the pump and to permit the escape of air upon the upstroke of the piston, the piston cap 13 and the gasket or disc plate 12, 100 are provided with air escape openings 29.

The base C includes the upstanding hollow cylindrical body 30 and the bottom wall 31, which is provided with outwardly extending ears 32, which define a relatively 105 large base plate for the pump and also foot rests for holding the pump cylinder or barrel A against movement during the operation of the piston B. The upper end of the cylindrical body 30 is provided with internal threads 33 so that the cylindrical body 10 of the pump valve A can be

threaded directly into the same. Directly below the threads 33 the body 30 is provided with a threaded bore 34, in which is threaded a nipple 35 which is provided with 5 the polygonal stop shoulder 36. If so desired, a suitable packing gasket 37, can be interposed between the shoulder 36 and the outer surface of the body 30. The nipple 35 extends inwardly into the body 30 and 10 is provided with an angular bent terminal 38, which forms a valve seat, the purpose of which will hereinafter more fully appear. The outer end of the nipple 35 protrudes outwardly of the body 30 and is provided 15 with an annular groove 39 and the outwardly extending portion of the nipple is adapted to receive a flexible tube 40. A suitable retaining ring 41 may be employed for forcing a portion of the flexible tube 20 40 into the groove 39 whereby slipping of the tube will be eliminated. The lower wall 31 is provided with an inwardly extending horizontal way 42 and a vertically disposed way 43 which terminates substantially 25 directly below the bent end 38 of the nipple 35. The horizontal way 42 is provided with internal threads for the reception of the nipple 44, which has attached thereto a suitable flexible hose 45. The hose 45 is 30 attached to the nipple 44 similar to or the same manner in which the hose 40 is connected to the nipple 35.

A single valve 50 is utilized for controlling the inlet and outlet of fluid into the 35 body 30 and the pump barrel or cylinder A, and as shown this valve includes a flat body 51 and a reduced stem 52 which is held in place on the lower wall by a suitable removable fastening element 53. This 40 valve 50 may be formed of any suitable material, such as rubber, leather or the like. The valve body 51 is normally adapted to rest over the vertically disposed way 43 and the upper surface of the way forms a valve 45 seat. It can be seen however, that on the up-stroke, when the fluid is sucked into the pump barrel, the valve will seat on the bent end 38 of the nipple and thus prevent the flow of water therethrough. The hose 40 50 may be formed of any desired length, and the upper end of the same is provided with a U-shaped nozzle 55, which is adapted to

be inserted into the radiator filling spout, and it can be seen that owing to the shape thereof, it will not be necessary to hold 55 the same in position by hand.

In operation of the improved pump, the tube hose 45 is extended to a stream or other body of the water and the nozzle 55 is inserted in the radiator filling spout of 60 the vehicle, and the piston is drawn up into the cylinder A. This lifts the valve 50 from off of the valve seat formed by the vertical way 43 and moves the same into tight engagement with the seat formed on 65 the inner end of the nipple 35. This prevents the sucking of air into the cylinder and permits the free flow of water into the same. The piston is then forced down which will forcibly move the valve 50 on 70 the seat formed by the vertical way 43 and water will be forced through the nipple 35 through the hose 40, nozzle 55 and into the radiator.

Changes in details may be made without 75 departing from the spirit or scope of this invention; but,

I claim:

1. In a pump, a cylinder, a base removably fitted on one end of the cylinder, the 80 base including a cylindrical body, and a bottom wall, the cylindrical body having a threaded bore formed therein, an outlet nipple fitted in said bore and extending into the cylinder, and having its inner end 85 provided with a valve seat, the bottom wall of the base being provided with an inlet passageway, and a single flap valve arranged to seat upon the valve seat and over the passageway. 90

2. In a base for pumps, a cylindrical body, a bottom wall, the bottom wall having an inlet port formed therein, and a valve seat for said port, an outlet nipple carried by the cylindrical body having the 95 inner end thereof extending into the body and the outer end thereof extending outwardly of the body, a downwardly extending valve seat formed on the inner end of the outlet nipple, a flexible valve secured 100 between the valve seats arranged to fit upon the valve seats at different times.

SAMUEL E. BURKETT.
